(57) **CLAIM**

The ornamental design for a shaved ice machine accessory, as shown and described.

DESCRIPTION

FIG. 1 is a perspective view of my new design, showing a first embodiment of a shaved ice machine accessory;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof;

FIG. 8 is a perspective view of my new design, showing a second embodiment of a shaved ice machine accessory;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and

FIG. 14 is a bottom plan view thereof;

FIG. 15 is a perspective view of my new design, showing a second embodiment of a shaved ice machine accessory;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The line shading in FIGS. 1-21 represents contour and not surface ornamentation.

The broken lines shown in the figures illustrate environmental or other features that form no part of the claimed design.

1 Claim, 21 Drawing Sheets
